UNITED STATES PATENT OFFICE

2,319,980

SAFETY RAZOR

Edmund L. Des Jardins, Chicago, Ill.

Application September 25, 1939, Serial No. 296,417

6 Claims. (Cl. 30—50)

My invention relates particularly to safety razors of the "double edged" type, although not limited to this use alone.

The primary object of the invention resides in the provision of a novel and efficient safety razor provided with a plurality of blades acting simultaneously in series whereby a close shave is quickly effected with relatively low blade pressure against the skin and without skin irritation or damage or tendency toward inducing ingrown hair, the invention contemplating the adaptation thereof to existing razors.

With this object in view, my invention consists in certain features of novelty in the construction, combination and arrangement of parts by which the said object and certain other objects, hereinafter appearing, are effected all as fully described with reference to the accompanying drawing, and more particularly pointed out in the appended claims.

In the said drawing—

Figure 1 is a partially assembled view in side elevation of a safety razor embodying my invention with the handle thereof broken away;

Figure 2 is a similar view with the razor fully assembled;

Figure 3 is a face view of the cap member of the razor;

Figures 4 and 6 are face views of the razor blades of my invention;

Figure 5 is a face view of the razor blade separator of my invention; and

Figure 7 is a face view of the guard member of the razor.

Referring to the drawing, 1 designates a conventional elongated safety razor cap member which is curved transversely and is provided with a central screw stud 2 and registering studs 3, these studs being arranged in alignment and intermediately and spaced longitudinally of the longitudinal edges of the cap member, all as is usual. See Figures 1, 2 and 3.

An elongated transversely curved guard member 4 is provided with a registering and securing slot 5 therethrough, arranged intermediately and extending longitudinally of the longitudinal edges thereof, the slot being provided with spaced enlargements 6 for registering and securing engagement with the studs 2 and 3 of the cap member in the assembly of the razor, as is usual. See Figures 1, 2 and 7. A bored handle 7 is screw-threaded on the screw stud 2 for securing the razor in assembly, as is usual.

In the assembly of the razor, a plurality of razor blades are employed with separating means

therebetween which are clamped and registered between the cap and guard members after the manner in which the conventional blade is clamped between the guard and clamp members.

The razor blade of my invention, as shown, is generally similar to the usual flexible double edged blades and is designated at 8. See Figures 1, 2, 4 and 6. This blade is elongated, is provided with cutting edges 9 at both longitudinal edges thereof, and is provided with a registering and securing slot 11 therethrough, arranged intermediately and extending longitudinally of the longitudinal edges thereof, the slot being provided with spaced enlargements 12 for registering and securing engagement with the studs 2 and 3 of the cap member in the assembly of the razor, as is usual.

The razor blade separator of my invention, as shown and designated at 13, is elongated and may be of any suitable flexible material, or may be of rigid material properly curved transversely, as designated in dash lines at 14 in Figure 1, and is provided with a registering and securing slot 15 therethrough, arranged intermediately and extending longitudinally of the longitudinal edges thereof, this slot being provided with spaced enlargements 16 for registering and securing engagement with the studs 2 and 3 of the cap member in the assembly of the razor as is the case with the blades, these engagements being involved as the securing and registering means of the assembled razor. See Figures 1, 2 and 5.

In the assembly of the razor, see Figures 1 and 2, the blades 8 with the separator 13 therebetween are clamped between the cap member 1 and the guard member 4, due to the handle 7 being screw-threaded on the screw stud 2. The screw stud 2 and the studs 3, engaging through the slot enlargements 6 of the guard member 4, the slot enlargements 12 of the blades 8 and the slot enlargements 16 of the separator 13, in cooperation with the handle 7 screw-threaded on the screw stud 2, secure the cap member, guard member, blades and separator in registered assembly, as shown in Figure 2.

Scavenging is accomplished in the following manner: The guard member 4 is provided with scavenging opening portions arranged between both longitudinal edges and the intermediate securing and registering slot 5 thereof and extending longitudinally of the longitudinal edges thereof and comprising apertures 17 therethrough adjacent the longitudinal edges thereof and spaced therealong. See Figure 7.

The upper razor blade 8 is, and for the pur-

pose of interchange and quantity production all of the razor blades are identical and are provided with scavenge opening portions arranged between both longitudinal or cutting edges 9 and the intermediate securing and registering slot 11 thereof and extending longitudinally of and adjacent the cutting edges and comprising apertures 18 therethrough adjacent the cutting edges and spaced therealong. See Figures 4 and 6.

The separator 13 is provided with scavenge opening portions arranged between both longitudinal edges and the intermediate securing and registering slot 15 thereof and extending longitudinally of the longitudinal edges thereof and comprising slots 19 spaced along the longitudinal edges thereof and extending inwardly therefrom. See Figure 5.

When the razor is assembled as shown in Figure 2, the scavenge openings of the blades, separator and guard member communicate with each other so that all of the blades are cleared of waste removed from the skin during the shaving operation.

In the use of the razor, the leading blade, guarded by the guard member 4, makes a first or rough cut, after which the trailing blade makes a second or finishing cut, the skin being guarded during both cuts. As a result, a close shave is effected without necessitating re-shaving, with resultant efficiency and less irritation to the skin, provision being made for the proper scavenging of all of the blades.

While I have thus described my invention, I do not wish to be limited to the precise details described, as changes may be made readily without departing from the spirit of my invention, but having thus described my invention, I claim as new and desire to secure by Letters Patent the following:

1. In a safety razor, the combination with elongated correspondingly disposed cap and guard members and associated securing and registering means arranged intermediately and extending longitudinally of the longitudinal edges thereof, of at least two correspondingly disposed elongated blades having cutting edges at both longitudinal edges thereof and an elongated separator of normally flat flexible material disposed correspondingly therewith and therebetween secured between said cap and guard members and provided with securing and registering openings at their intermediate longitudinally extending portions for cooperation with said securing and registering means, said guard member, the blade

next thereto, and said separator being provided with communicating scavenge openings arranged between both longitudinal edges thereof and said registering and securing openings and means and extending longitudinally of said cutting edges.

2. In a safety razor, the combination with elongated correspondingly disposed cap and guard members and associated securing and registering means arranged intermediately and extending longitudinally of the longitudinal edges thereof, of at least two correspondingly disposed elongated blades having cutting edges at both longitudinal edges thereof and an elongated separator disposed correspondingly therewith and therebetween secured between said cap and guard members and provided with securing and registering openings at their intermediate longitudinally extending portions for cooperation with said securing and registering means, said guard member, the blade next thereto and said separator being provided with communicating scavenge openings arranged between both longitudinal edges thereof and said registering and securing openings and means, the scavenge openings of said blade comprising apertures therethrough adjacent the cutting edges thereof and spaced therealong, and the scavenge openings of said separator comprising slots spaced along the longitudinal edges thereof and extending inwardly therefrom.

3. A safety razor blade separator of normally flat flexible material provided with a scavenge opening portion extending along an edge thereof.

4. A safety razor blade separator of normally flat flexible material provided with a scavenge opening portion comprising slots spaced along an edge thereof and extending inwardly therefrom.

5. An elongated safety razor blade separator of normally flat flexible material having a securing and registering opening portion arranged intermediately and extending longitudinally of the longitudinal edges thereof and provided with scavenge opening portions extending along both longitudinal edges thereof.

6. An elongated safety razor blade separator of normally flat flexible material having a securing and registering opening portion arranged intermediately and extending longitudinally of the longitudinal edges thereof and provided with scavenge opening portions extending along both longitudinal edges thereof and comprising slots spaced along the longitudinal edges thereof and extending inwardly therefrom.

EDMUND L. DES JARDINS.
